UNITED STATES PATENT OFFICE.

ALVA J. FISHER, OF CHICAGO, ILLINOIS, ASSIGNEE TO HURLEY MACHINE COMPANY,
OF CHICAGO, ILLINOIS, A CORPORATION OF ILLINOIS.

AGITATOR OR DOLLY FOR WASHING-MACHINES.

1,211,128.

Specification of Letters Patent.

Patented Jan. 9, 1917.

Application filed September 14, 1916. Serial No. 126,171.

To all whom it may concern:

Be it known that I, ALVA J. FISHER, a citizen of the United States, and a resident of Chicago, in the county of Cook and State 5 of Illinois, have invented certain new and useful Improvements in Agitators or Dollies for Washing-Machines; and I do hereby declare that the following is a full, clear, and exact description thereof, reference being 10 had to the accompanying drawings and to the letters of reference marked thereon, which form a part of this specification.

This invention relates to improvements in agitators or dollies for washing machines 15 and consists of the matters hereinafter described and more particularly pointed out in the appended claims.

The object of the invention is to provide an improved construction of agitator or 20 dolly having means to protect the agitator or dolly shaft from entanglement with the clothes, in the operation of the washing machine.

In the drawings: Figure 1 is a perspective 25 view of one form of my improved agitator or dolly. Fig. 2 is a view representing a partial vertical section through a washing machine tub of the alternating rotary type having a dolly shaft depending from the 30 tub lid and provided with my improved dolly. Fig. 3 is a partial vertical central section through my improved form of dolly, on an enlarged scale. Fig. 4 is a view representing a transverse section through Fig. 3 35 in a plane indicated by the lines 4—4 of Fig. 3, the section appearing as looked at from below the dolly head. Fig. 5 is a view representing my improvement applied to a dolly in a washing machine where the dolly 40 shaft projects upwardly through the bottom of the tub. Figs. 6 and 7, respectively, are detail sectional views representing modified forms of my invention.

My improved dolly as shown herein is illustrated as applied to a washing machine of 45 the alternating rotary type wherein the dolly shaft is given an alternating rotary movement in a familiar manner.

Referring now to that embodiment of my 50 invention illustrated in the drawings: 10 indicates the dolly head; 11 indicates the depending fingers or pins attached to said head; 12 indicates the dolly shaft which, in the embodiment illustrated in the drawings, 55 is non-rotatively and slidably engaged in a

bearing aperture 13 (see Fig. 4) in the dolly head; 14 indicates the tub lid from which the shaft 12 depends and in which it is rotatively mounted; 15 indicates the body of the tub and 16 indicates a gear or pinion 60 fixed to the top of the dolly shaft through which the alternating rotary movement is imparted to the dolly shaft and dolly by means of any suitable or well known gearing (not shown). A disk 17, fixed to the 65 bottom end of the dolly shaft, limits the downward movement of the dolly on its shaft. 18 indicates the level of the clothes in the tub.

The construction thus far described is familiar and old.

In the operation of the washing machine, there is not only the alternating rotary motion of the dolly with the dolly shaft, but there is also the sliding up and down movement of the dolly head on the dolly shaft, due to the variation in the level 18 of the clothes in the tub. During the washing operation, the clothes are apt to engage the dolly shaft 12 and to become entangled between the disk 17 and the dolly head 10 or to be caught in the bearing opening in the head 10. In the case of light weight or delicate articles or fabrics, this is apt to result in tearing, ripping or cutting. In my improved dolly, I provide a flexible curtain 19, which depends from the bottom of the dolly head 10 and is attached to the dolly so as to surround the bearing opening 13 and the dolly shaft 12. This curtain as illustrated 80 in the embodiment of my invention shown in the drawings, is in the form of a flexible tube made of canvas or like heavy material. The bottom of the dolly head 10 is provided with an annular groove 20 surrounding the 85 bearing opening 13 (see Figs. 3 and 4), forming in effect a stud 21 upon which the upper end of the flexible tube 19 is engaged. Said tube is held as shown on said stud by means of a split spring ring 22. This construction 90 provides detachable means for connecting the tube to the head so that the protecting tube or curtain may be removed and replaced after it has been worn out in operation.

The curtain 19 surrounds and protects the dolly shaft 12 and the bearing opening 13 on all sides and is preferably made longer than the pins or fingers 11 on the dolly head, so as to depend below said fingers. In the 95

operation of the washing machine, this curtain, depending below the dolly shaft and below the fingers 11, engages the clothes 18 first and crumples as indicated in Fig. 2. 5 This in no way interferes with the operation of the dolly head, but apparently at all times protects the dolly shaft.

In Fig. 5 I have shown the improved dolly as applied to a washing machine in which 10 the operating shaft projects upwardly through the bottom wall of the tub. In this case, 12^a indicates the dolly shaft. The other parts are indicated as before. The operation here is the same as in the other case. 15 In the case of the dolly which depends through the lid as shown in Figs. 1 to 4 inclusive, of the drawings, the tubular curtain 19 may be closed at its bottom end as illustrated in Figs. 6 and 7. In Fig. 6 the bottom 20 end of the curtain 19 is shown as closed by a horizontal bottom wall 19^a which is secured in place by an inturned seam, while in Fig. 7 the said bottom end of the curtain is closed by a line of stitching 19^b. In the case of a 25 closed end curtain the bottom end of the dolly shaft 12 is prevented from engaging with the clothing being operated upon, thus eliminating tearing or marring of said clothing.

30 The many advantages of my improved dolly will be apparent from the foregoing description.

While in describing my invention I have referred to details of mechanical construction and arrangement, it will be understood that the invention is in no way to be limited thereby, except as may be pointed out in the appended claims.

I claim as my invention:

40 1. An agitator for washing machines adapted to be attached to an operating member, said agitator comprising an operating head and a flexible curtain attached to and depending from said head and adapted to 45 protect said operating member.

2. An agitator for washing machines

adapted to be non-rotatively and slidably attached to an operating member, said agitator comprising a head provided with a bearing opening and a flexible curtain attached to and depending from said head, said curtain surrounding said bearing opening and being adapted to protect said operating member. 50

3. An agitator for washing machines 55 adapted to be attached to an operating member, comprising a head provided with depending pins or fingers, said head having a bearing opening for an operating member and a flexible curtain attached to and depending from the bottom of said head, said curtain consisting of a tube which depends below the ends of said pins or fingers. 60

4. An agitator for washing machines adapted to be attached to an operating member, comprising a head provided with depending pins or fingers, said head having a bearing opening for an operating member and a flexible curtain detachably connected with and depending from the bottom of said 70 head, said curtain consisting of a tube which depends below the ends of said pins or fingers. 75

5. An agitator for washing machines adapted to be attached to an operating member, comprising a head provided with depending pins or fingers, said head having a bearing opening for an operating member and a flexible curtain detachably connected with and depending from the bottom of said 80 head, said curtain consisting of a tube having a closed bottom end which depends below the ends of said pins or fingers.

In testimony, that I claim the foregoing as my invention I affix my signature in the 85 presence of two witnesses, this 31st day of August A. D. 1916.

ALVA J. FISHER.
